FORM SETTER FOR SETTING SIDEWALK AND DRIVEWAY FORMS

Robert S. Hughes, 28275 Ranchwood, and James A. Sheehan, 28225, Ranchwood, both of Birmingham, Mich.

Filed June 15, 1959, Ser. No. 56,345

Term of patent 14 years

(Cl. D51—1)

Fig. 1 is a side elevational view of a form setter for setting sidewalk and driveway forms embodying the new design; and

Fig. 2 is a rear elevational view; and

Fig. 3 is a front elevational view; and

Fig. 4 is a bottom view.

The characteristic features of our design for the form setter disclosed reside in the clamp and handle portions connected to the channel portion and centrally disposed on the stake having the configurations shown.

We claim:

The ornamental design for a form setter for setting sidewalk and driveway forms, substantially as shown and described.
